TRAIN TELEPHONE SYSTEM FOR SIMULTANEOUS COMMUNICATIONS

Archibald G. Shaver, Chicago, Ill.

Application September 19, 1928, Serial No. 306,905
Renewed February 25, 1932

29 Claims.

(Cl. 246—8)

This invention relates to a system for carrying on communication between different parts of a railway train; between two railway trains operating on the same track system; and between a railway train and the wayside. More specifically it admits of two or more separate and distinct sets of communications taking place at the same time over the same general system, as for example:—Communication may be carried on between 5 a dispatcher in his office on the wayside and either the conductor or engineman, or both of them, on a train at the same time that communication is taking place between a passenger on the train and some person in a wayside station. Or it may be that communication is taking place between 10 the engineman at the head of a train and the conductor at the rear of the train, and, at the same time communication is under way between a passenger on the train and some person in a 15 wayside station, or on another train.

A principal object of the present invention is the provision of a system embodying improvements in the communicating means, employed as a part of the train operating system, described 20 and claimed in the copending application of 25 Archibald G. Shaver, Serial No. 227,932 filed October 22, 1927, in which communication may take place between the engineman at the head of the train and the conductor at the rear of the train, 30 or between either of these latter two, or both of them, and the train dispatcher while the train is moving or standing still and the dispatcher is in his office. The present case also represents a 35 further development of my train telephone system application, filed September 7, 1928, Serial No. 304,483.

A further object of the invention relates to the provision of means for carrying on a plurality of communications over the same general system of connecting circuits without detrimental interference between the various sets of communications.

The improvements in the present invention center about the application of audio and radio frequency means to the novel means provided for so connecting two parts of a train, two trains, and a train and a wayside station together for communication purposes, that two or more separate and different communications may be carried 50 on at the same time over the same communicating medium.

In the accompanying drawings, which show a preferred embodiment of the invention:

Figure 1 is a schematic diagram of the circuits 55 and equipment on one or both ends of the train.

Figure 2 is a diagrammatic showing illustrative of the circuits and equipment on the track connected with the circuits and equipment in the wayside stations, for coordination with the train carried sets illustrated in Figures 1 and 3.

Figure 3 illustrates the usual arrangement of 5 circuits and equipment for the head end of a train.

Figure 4 is another and optional arrangement 10 of circuits and equipment on a train.

Figure 5 is a diagrammatic showing illustrative 15 of circuits and equipment on the wayside to coordinate with the train carried set illustrative in Figure 4.

The system will now be described as one for 20 telephone communication in which audio frequencies are used for the business of the railroad (for communication between conductors and enginemen and the train dispatcher); and radio frequencies, of a band somewhat higher than the 25 audio band, are used for commercial purposes (for communications between passengers on trains and persons in wayside stations, and between passengers on different trains).

In Figure 1, the boundary line BY10 encloses 25 the radio frequency equipment and the boundary line BY11 encloses the audio frequency equipment, all on the train. T3 is the radio frequency transmitting means in a circuit including conductors 200 and 208, modulator and oscillator 30 M&O3, conductors 201 and 207, filter FL2, conductors 202 and 203, inductor IND4, conductor 204, inductor IND3 and conductors 205 and 206. R3 is a radio frequency receiving means in a circuit including conductors 210 and 213, detector DET3, 35 conductors 211 and 214, filter FL3, conductors 212, 202 and 203, inductor IND4, conductor 204, inductor IND3 and conductors 205 and 215. The audio frequency system comprises transmitting 40 and receiving sets Z3 in a circuit including conductor 217, filter FLA, conductors 216 and 203, inductor IND4, conductor 204, inductor IND3 and conductors 205 and 218. The inductors IND3 and IND4 are of suitable design and so positioned that each rides over a track rail TR 45 in inductive cooperation with said track rail through an air gap. While these inductors are here shown connected in series, they may be connected in parallel; and the system is operative if only one inductor is used.

In Figure 2, two complete intermediate circuits, B—C and D—E, and parts of two others, A and F—G, are illustrated. TR are the track rails of a stretch of track. CA represents the rear end and LO the front end of a train. Also, these 55

same symbols, minus the connecting line, may be understood to represent two trains in the same intermediate circuit, CA being one train and LO the other train. TAR is a control relay which is deenergized during and by the presence of a train in intermediate circuit or section A, but otherwise energized. TB, TD and TF are track circuit relays of the usual sort normally energized, but deenergized, whenever there is a train in their respective sections B, D and F. TA, TC and TE are telephone transformers each with a primary P and a secondary S. L is a conductor extending throughout the length of the stretch of track which is equipped for train communication. D1 and D2 represent the two conductors of a wayside telephone system, as for example the well-known dispatcher's telephone and selective system now in use on nearly all railroads. SL is a selector relay operated by the selective system, which is ordinarily a part of the dispatcher's telephone system for calling operators in wayside stations to the phone. 46 and 47 are circuit making contacts normally open but closed when SL is operated by the prescribed code in the selective system when DSA is operated.

For the intermediate circuit A the partial circuit conductors L and 32, secondary coil S of transformer TA, conductor 33, contact 31 normally closed, conductor 30, condensers AK and connections to track rails TR, are illustrated. That part of intermediate circuit A not shown is like that illustrated and described for intermediate circuit F—G.

The intermediate circuit B—C comprises track rails TR, connections to condensers AK, conductor 30, contact 31, normally closed, conductors 33, L and 42, secondary coil S of transformer TC, conductor 43, contact 41 normally closed, conductor 40, condensers AC and connections to the track rails.

The intermediate circuit D—E comprises track rails TR, connections to condensers AC, conductor 40, contact 41 normally closed, conductors 43, L and 52, secondary coil S of transformer TE, conductor 53, contact 51 normally closed, conductor 50, condensers AE and connections to the track rails.

For the intermediate circuit F—G the partial circuit track rails TR, connections to and condensers AE, conductor 58, contact 51 normally closed and conductors 53 and L, are illustrated. That part of intermediate circuit F—G not shown is like that illustrated and described for intermediate circuit A.

The heavy lines across the track rails TR as indicated by 24 are insulated joints fixing the limits of the track section circuits A, B, D, F, etc. In order to make the track rails part of the intermediate circuits complete for conducting the communication currents, a condenser TK is connected around each insulated joint as illustrated.

Within the boundary line BY12 are represented the radio frequency circuits and equipment in the wayside station. T4 is the radio frequency transmitting means in a circuit including conductors 228 and 229, modulator and oscillator M&O4, conductors 227 and 230, filter FL4, conductors 225, D1 and 55, condenser EC, primary coil P of transformer TE, and conductors 54, D2, 219 and 226. R4 is a radio frequency receiving means in a circuit including conductors 221 and 222, detector DET4, conductors 220 and 223, filter FL5, conductors 224, 225, D1 and 55, condenser EC, primary coil P of transformer TE and conductors 54, D2 and 218.

Within the boundary line BY13 are represented the audio frequency circuits and equipment in the wayside station or dispatcher's office. Z4 is the transmitting and receiving set in a circuit including conductor 232, filter FLB, conductors 231, 224, 225, D1 and 55, condenser EC, primary coil P of transformer TE, and conductors 54, D2, 219 and 233.

Switch J1 manually operable, is included in each of the circuits for T4, R4, and Z4.

For the several intermediate circuits shown a different method of connecting the transformers to the telephone conductors D1 and D2 is indicated. Transformer TE is in permanent connection. Transformer TC is connected only when the selective system device DSA is operated to energize relay SL to close contacts 46 and 47. Transformer TA is connected to conductors D1 and D2 whenever there is a train in section A so that relay TAR is deenergized. In actual practice one, any two or all three of these methods of connection may be used within the completed system.

DSA represents selective apparatus of the type now used in railway telephone systems for dispatching trains. This apparatus is operated to connect the conductors D1 and D2 to the transformers, as TC, whenever it is desired by the dispatcher to hold conversation with a train in a particular intermediate section which is equipped for selective connection.

J1 is a disconnecting switch shown merely as a convenience for disconnecting the station equipment from the outside lines.

Figure 3 illustrates the equipment which will usually be installed on the head end of the train and it is for audio frequency operation. Generally the equipment on the head end of the train is for the use of the engine crew in conversing with the conductor and dispatcher, hence from it only one conversation at a time is necessary. In any case where more than one set of communications is to be under way at one time from the head end of the train, the equipment and circuits illustrated in Figure 1 would be used. Z5 is the transmitting and receiving set in a circuit including, conductor 237, filter FLB, conductor 238, inductor IND6, conductor 235, inductor IND6 and conductor 234. The inductors IND5 and IND6 are also positioned to ride over the track rails TR in inductive cooperation with said rails through an air gap. These inductors are of suitable design. They may also be operated in parallel connection, and only one may be desirable in certain installations.

Figures 4 and 5 are illustrative of another type of system for making possible the simultaneous transmitting and receiving of a plurality of communications to and from a train. In this system audio frequency is used for one channel of communication and radio frequency for another channel. It differs essentially from the system heretofore explained, as illustrated in Figures 1, 2 and 3, in that each channel of communications has a circuit of its own and each track rail is devoted to a different intermediate circuit so that for each section of track there are two parallel intermediate circuits, one of these intermediate circuits being used for the audio frequency communication and the other for the radio frequency communication. These intermediate circuits connect to different sets of wayside lines.

In Figure 4 the boundary line BY7 encloses the entire equipment on the train for one set. If there is a second set, it may be a duplication.

of the one shown. Ordinarily, however, the set at the head of the train will comprise the audio frequency equipment only which is that including the transmitting and receiving equipment Z7, the filter FLC, the inductor IND8 and the connecting circuit composed of the conductors 308 and 301.

The radio frequency set comprises the transmitting apparatus T5 and the receiving apparatus R5 connected to the inductor IND7. The transmitting apparatus T5 is in a circuit including modulator and oscillator M&O5, filter FL6, conductors 302 and 306, inductor IND7 and conductors 307 and 308. The receiving apparatus R5 is in a circuit including detector DET5, filter FL7, conductors 304 and 308, inductor IND7 and conductors 307 and 308. The inductors IND7 and IND8 are of suitable design for the frequencies used and positioned to ride over the track rails TR2 and TR1 respectively in inductive cooperation with said rails through an air gap.

Where both ends of the train are equipped with communicating sets, the inductors will be positioned in accordance with their respective intermediate circuits. If one end of the train is equipped for audio frequency operation only, the inductor for that set will be positioned over rail TR1. In the case of trains operating in both directions on one track, it will be necessary that inductors be provided for each direction of operation; or the inductors may be interchanged in some manner suitable for the frequencies involved.

Figure 5 shows how the equipped stretch of track is divided into territories or sections as A1, B1—C1, D1—E1 and F1—G1, each comprising two intermediate circuits, one for each rail. As illustrated, A1 and F1—G1 have partial intermediate circuits and B1—C1 and D1—E1 complete intermediate circuits.

For the audio frequency operation the intermediate circuits are:

Section A1, partial circuit only shown, conductors L6 and 180, transformer RA1, conductor 183, contact 181 normally closed, conductor 182 and condenser to track rail TR1. That part of this intermediate circuit A1 not shown is like that illustrated and described for intermediate circuit F1—G1, including, conductors L5 and 181, contact 183, conductor 186, condenser and track rail TR1.

Section B1—C1, complete circuit, track rail TR1, condenser, conductor 182, contact 181 normally closed, conductors 183, L5 and 184, transformer RC1, conductor 187, contact 185 normally closed, conductor 186 and condenser to track rail TR1.

Section D1—E1, complete circuit, track rail TR1, condenser and conductor 188, contact 185 normally closed, conductors 187, L5 and 188, transformer RE1, conductor 181, contact 189 normally closed, conductor 180, condenser and track rail TR1.

Section F1—G1, partial circuit only shown, track rail TR1, condenser, conductor 180, contact 189 normally closed, conductors 181, L5, etc. That part of this intermediate circuit F1—G1 not shown is like that partial circuit illustrated and described for intermediate circuit A1 including track rail TR1.

Included in the track rail TR1 are insulated joints, similar to those referred to by symbol 24 in Fig. 2, limiting the various track circuit sections A1, B1, D1, F1, etc. In order that the communicating current will have an uninterrupted path through the track rail TR1, condensers are

connected as illustrated in Fig. 5, around all insulated joints.

For the radio frequency operation the intermediate circuits are:

Section A1, partial circuit only shown, conductors L6 and 180, transformer TA1, conductor 183, contact 181 normally closed, conductor 182, and condenser to track rail TR2. That part of this intermediate circuit A1 not shown is like that illustrated and described for intermediate circuit F1—G1, including, conductors L6 and 181, contact 189, conductor 180, condenser and track rail TR2.

Section B1—C1, complete circuit, track rail TR2, condenser, conductor 182, contact 181 normally closed, conductors 183, L6 and 184, transformer TC1, conductor 187, contact 185 normally closed, conductor 186 and condenser to track rail TR2.

Section D1—E1, complete circuit, track rail TR2, condenser, conductor 186, contact 185 normally closed, conductors 187, L6, and 188, transformer TE1, conductor 181, contact 189 normally closed, conductor 180 and condenser to track rail TR2.

Section F1—G1, partial circuit only shown, track rail TR2, condenser, conductor 180, contact 189 normally closed, conductors 181, L6, etc. That part of the intermediate circuit F1—G1 not shown is like that partial circuit illustrated and described for intermediate circuit A1, including track rail TR2.

Included in the track rail TR2 are insulated joints limiting the various track circuit sections A1, B1, D1, F1, etc. In order that the communicating current will have an uninterrupted path through the track rail TR2, condensers are connected around the insulated joints as illustrated in Fig. 5.

Within the boundary line BY8 are represented the radio frequency apparatus and circuits in a wayside station. T7 is the radio frequency transmitting means in a circuit including, a modulator and oscillator M&O7, filter FL8, and conductors 308 and 312 and 309 and 313 connecting to telephone conductors D7 and D8 which extend along the equipped railway track. R7 is a radio frequency receiving means in a circuit including, detector DET7, filter FL9 and conductors 310 and 312 and 311 and 313 connecting to conductors D7 and D8.

Within the boundary line BY9 are represented the audio frequency apparatus and circuits in a wayside station or dispatcher's office. Z6 is the transmitting and receiving set in a circuit including filter FLD and conductors 315 and 314 connecting respectively to telephone conductors D5 and D6 which extend along the equipped railway track.

CA1 represents the rear end of a train and LO1 the front end. The same symbols minus the connecting line may be understood to represent two trains in the same intermediate circuit, CA1 being one train and LO1 the other.

DSE represents the selective equipment on the wayside or in the dispatcher's office used for operating the selector relays SLC and SLE.

TAR1, TCR1 and TER1 are control relays normally energized, but deenergized with the presence of a train in their respective sections A1, B1—C1 and D1—E1. TB1, TD1 and TF1 are track circuit relays of the usual sort normally energized, but deenergized with a train in their respective sections B1, D1 and F1.

TA1, TC1 and TE1 are telephone transformers.

designed for radio frequencies, the secondaries of each being in the normally closed radio intermediate circuits for sections A1, B1—C1 and D1—E1 respectively, and the primaries being connected to wayside telephone conductors D7 and D8 whenever relays TAR1, TCR1 and TER1 respectively are deenergized operating their back contacts to the closed position. When back contacts 162 and 163 are closed, leads 171 and 172 of primary coil P of transformer TA1 are connected to conductors 175 and 176 respectively. When back contacts 166 and 167 are closed, leads 192 and 193 of primary coil P of transformer TC1 are connected to conductors 194 and 195 respectively. When back contacts 168 and 169 are closed leads 198 and 199 of primary coil P of transformer TE1 are connected to conductors 196 and 197 respectively. Conductors 176, 195 and 197 are connected to conductor D7. Conductors 175, 194 and 196 are connected to conductor D8.

The transformers RA1, RC1 and RE1 are designed for audio frequency, the secondaries of each being in the normally closed audio intermediate circuits for sections A1, B1—C1 and D1—E1 respectively. Leads 173 and 174 from transformer RA1 are connected to telephone conductors D6 and D5 by the closing of contacts 164 and 165 on conductors 177 and 178 respectively. Transformer RC1 is bridged across telephone conductors D5 and D6 when selector relay SLC is operated by the train dispatcher to close contacts 316 and 317. Transformer RE1 is similarly bridged across the conductors D5 and D6 by the closing of contacts 318 and 319 in the operation of selector relay SLE.

In the system illustrated in Figures 4 and 5, the use of one radio frequency band and one audio frequency has been referred to for transmitting and receiving simultaneous sets of communications. Since there are two separate and distinct communicating circuits or channels throughout the system, it is readily apparent that audio frequencies alone or radio frequencies in the same band, or radio frequencies in different bands may be used, instead of the one radio frequency band and one audio frequency band, for simultaneously carrying on a plurality of sets of communications.

50 Operation

Reference is to the system disclosed in Figures 1, 2 and 3:

Assume that the train is in section A and that the dispatcher, with the equipment represented within the boundary line BY13, desires to give orders to the train conductor using the equipment represented within the boundary line BY11. Also assume that at the same time a passenger on the train, using the equipment represented within the boundary BY10, starts a conversation with a person in a wayside station, using the equipment within the boundary line BY12.

65 The train being in section A, relay TAR is deenergized closing contacts 35 and 36 connecting transformer TA with conductors D2 and D1.

The dispatcher makes it known to the train conductor through the equipment Z4, by causing electric communication impulses to be set up in the channel for communication hereinafter described, that he desires to communicate with him. The train conductor receives the signal through the receiving equipment of Z3, and answers through the transmitting equipment of

Z3, the dispatcher receiving the signals in his equipment Z4. Communication between the dispatcher and train conductor is now carried on. The channel for communication between the dispatcher and train conductor comprises transmitting and receiving set Z4, conductors 233 and 219, conductors 232, 231, 224 and 225, conductors D1 and D2 to transformer TA, intermediate circuit of A already described, the inductors IND3 and IND4 and conductors 204, 205, 218, 203, 216 and 217, and transmitting and receiving set Z3. Since this communication is carried on at audio frequency filters FLB and FLA are adjusted to let electric currents of audio frequency through, but none other. Since filters FL2, FL3, FL4 and FL5 are adjusted for the particular radio frequency band used in this set up, they do not pass electric currents at audio frequency; hence receiving equipments R3 and R4 are not disturbed by the communications transmitted at audio frequency.

In the meantime the passenger with transmitter T3 and receiver R3 has entered into communication with a person using transmitter T4 and receiver R4. The channel for these communications is also via the inductors IND3 and IND4, the intermediate circuit of A including the transformer TA, and the conductors D1 and D2, and vice-versa. Since this communication is carried on at radio frequency and the filters 30 FLB and FLA are adjusted for audio frequency only, electric currents of the radio frequency band used are not passed into the circuit of Z3 and Z4; hence the communication being carried on between the dispatcher and train conductor 35 is not disturbed by the communication taking place between the passenger and the wayside person.

In the operation of the system, electric currents induced into the intermediate circuits 40 through the transformers, as TA, set up a field of electro-magnetic impulses surrounding the track rails TR. This electro-magnetic field influences the inductors on the train to set up currents of similar impulses in the circuits of the inductors, thus affecting the receiving apparatus on the train.

In the case of transmitting from the train, the electric currents in the inductor circuits are transmitted inductively into the track rails and thus into the intermediate circuits and through the transformers, as TA, to the circuit including the conductors D1 and D2 and the wayside receiving equipment, affecting the latter to give the required signals.

While the train is in section A, the intermediate circuit of A being automatically connected to the wayside circuit, including conductors D1 and D2 leading to the wayside stations, communications may be freely carried on and at will between the train and the wayside, either station initiating the communication.

Assume the train to be in section B—C and that simultaneous communication is entered into between the train conductor at the rear of the 65 train CA and the engineman at the head of the train LO, and between a wayside person and a passenger on the train.

The conductor initiates the communication by operating the transmitting equipment of Z3. 70 This sets up audio frequency current in the circuit affecting the inductors IND3 and IND4 to induce audio frequency impulses into the track rails TR, such that the intermediate circuit of B—C heretofore described is energized with audio 75

frequency current. As the inductors IND5 and IND6 at the head of the train LO are in inductive relation with the track rails TR, audio frequency current in these track rails is induced into the circuit of said inductors and the communication is received by the engineman at Z5. When the engineman replies to the train conductor, the audio frequency current initiated by him through the transmitting equipment of Z5 in the circuit 10 for the inductors IND5 and IND6 is induced into the intermediate circuit B—C and reinduced from said circuit into the circuit of inductors IND3 and IND4 thus affecting the receiving apparatus Z3 so that the conductor hears the engineman's 15 signals.

For the wayside person to communicate with the passenger, selector relay SL must first be operated to close the contacts 46 and 47 which is done by operating the selector from the proper 20 code key in the selector system generally designated as DSA. The closing of the contacts 46 and 47 may also be done direct by the wayside person in the use of the dial system of an automatic telephone system identically as is now 25 accomplished in machine switching for connecting one subscriber with another in many of the present day telephone exchanges.

With contacts 46 and 47 closed transformer TC is connected to wayside communicating circuit 30 conductors D1 and D2. The wayside person may now communicate with the passenger through transmitting equipment T4, conductors D1 and D2, transformer TC, intermediate circuit B—C, inductors IND3 and IND4 and receiving apparatus R3. The passenger may respond into transmitter T3, through the same channel described, to the receiver R4.

Since filters FL2, FL3, FL4 and FL5 are adjusted to the radio frequency band and will not pass the audio frequency and since the filters FLA and FLC are adjusted to the audio frequency and will not pass the radio frequency band, the simultaneous communication between train conductor and engineman and between 45 wayside person and passenger may be carried on without interference, one with the other.

Assume that CA and LO are two different trains, but both in section B—C, and simultaneous conversation takes place between train conductor of LO and train conductor of CA and between a passenger on LO and a passenger on CA. The procedure and method for communicating between the two train conductors is the same as already explained for communication 50 between the train conductor and engineman of the same train. The procedure and method for communicating between the passengers of the two trains is similar to that already explained for the communication between the train conductor and engineman of the same train, except radio frequencies are used for the passenger to passenger communication. Because the filters of the audio frequency system will not pass the radio currents and the filters of the 55 radio frequency system will not pass the audio currents, the two sets of communications may be carried on simultaneously. A set of communications, as herein referred to, consists of the messages exchanged between two persons communicating together.

Refer now to the system disclosed in Figures 4 and 5:

Assume the train to be operating through the section B1—C1 as illustrated, being equipped on the rear end CA1, as indicated in Figure 4, and

that simultaneous communications are carried on between the train dispatcher, at the station enclosed in boundary BY9, and the train conductor, using transmitting and receiving apparatus Z1, and between a wayside person, using transmitting apparatus T7 and receiving apparatus R1, and a passenger on a train using transmitting apparatus T5 and receiving apparatus R5.

The dispatcher must initiate the communication with the train conductor by first operating his selective equipment DSE to close contacts 316 and 317 of selector relay SLC, which connects the wayside circuits, conductors D5 and D6, to the transformer RC1 in the intermediate circuit including track rail TR1 of section B1—C1. Through the transmitting equipment of Z6 the dispatcher may now send signals to the train conductor, the channel of communication being conductors D5 and D6, transformer RC1, intermediate circuit B1—C1 including 15 transformer RC1 and track rail TR1 already described, inductor IND8 and the circuit to receiving equipment Z1. The train conductor by operating the transmitting equipment of Z1 may reply to the dispatcher through the same channel 20 of communication, sequence reversed, for reception by the dispatcher in the receiving apparatus of Z6.

While the train is within the section B1—C1, control relay TCR1 is deenergized closing its contacts 166 and 167 connecting the wayside telephone circuit D1 and D8 to transformer TC1 so that the wayside system including the station within the boundary line BY8, is connected to the intermediate circuit of section B1—C1 including 30 transformer TC1 and track rail TR2. Through the transmitting equipment T7 the wayside person may send signals to the passenger, the channel of communication being conductors D1 and D8, transformer TC1, intermediate circuit of B1—C1 including track rail TR2, inductor IND7 and circuit to receiving equipment R5. The passenger by communicating through transmitting equipment T5 may reply through the same channel, in reversed sequence, to the wayside person at the receiving equipment R1. 35

As heretofore explained, the operation for communication between train equipments T5—R5 and wayside equipments T7—R7 is by a band of radio frequency while the operation for communication between train equipment Z1 and wayside equipment Z6 is by audio frequency. The filters FLC and FLD are arranged to pass audio frequency. This provision for two different frequencies is made mainly for the purpose of preventing interference, as cross talk, which might result in some cases, particularly as between the track rails TR1 and TR2.

There may be simultaneous communications consisting of a conversation between the rear end CA1 and the front end LO1 of the train and a conversation between a passenger on the train and a person on the wayside. The front end of train must have an equipment identical with inductor IND8 and its circuits including transmitting and receiving equipment Z1. The train conductor talking into transmitter equipment Z7, has his message conveyed by audio frequency via inductor IND8, track rail TR1 and intermediate circuit, inductor IND8 and circuits on front of the train to receiving apparatus Z1 on front of the train where the message is received by the engineman. The engineman replies to the train 70

conductor through the same channel of communication, sequence reversed. While the conversation between the train conductor and engineerman is going on the passenger talks into transmitting equipment T_6 to the wayside person and his communication is carried via inductor IND_1 , track rail TR_2 and intermediate circuit B_1-C_1 , transformer TC_1 , wayside circuit conductors D_1 and D_8 and receiving equipment R_7 . The wayside person replies to the passenger by talking into transmitter T_7 and his communication is carried by the channel just described, in the reverse sequence, to receiving apparatus R_8 .

Conversations between parties on two different trains in the same intermediate circuit are conducted in the same manner as between head end and rear end of train. Two sets of conversations may be carried on at the same time, track rail TR_1 and its intermediate circuit being used as a channel for one set, and track rail TR_2 and its intermediate circuit being used as the channel for the other set. A set of conversations as here termed consists of the messages exchanged between two persons talking together.

As illustrated in Figures 4 and 5 the train circuits and the wayside circuits for one channel of communication, that carrying radio frequency, are always in operative relation as the train progresses over the railroad, the train automatically connecting the intermediate circuits with the wayside circuits as it passes through the section for each circuit. For the other channel of communication, that carrying audio frequency, the train circuits and the wayside circuits are always in operative relation while the train is in section A_1 , because of the train on the track rails automatically connecting the wayside circuit with the intermediate circuit through relay TAR_1 ; but for sections B_1-C_1 and D_1-E_1 the selective system must be operated in order to establish operative relationship between the wayside and train circuits for the audio frequency.

These various methods of coordinating wayside and train carried circuits are typical. Any one method or any two or more of the several methods indicated, may be used, dependent upon the local conditions existing on the railroad equipped. For the conduct of the railroad business, it is generally best to provide an arrangement which will allow the greatest possible freedom for intra-train (head end to rear end) and inter-train (train to train) communication and at the same time give the train crew an occasional opportunity to initiate a conversation with the dispatcher. With the selective system the dispatcher can always get into communication with a train. After the selective system has been operated connecting the wayside system with the intermediate circuit and communication has ceased, the wayside system is disconnected from the intermediate circuit by again operating the selective system.

The condition existing where a train passes from one intermediate circuit to another is fully described in my copending applications Serial No. 227,932 filed October 22, 1927 and Serial No. 304,483 filed September 7, 1928.

Referring to Figures 2 and 5, a train in passing from one intermediate circuit to another automatically opens the cross connection from the parallel conductor L to the track rails so that during the interval of passing these two adjacent intermediate circuits are thrown together into

one enlarged intermediate circuit or communicating zone.

This condition may be specifically illustrated by referring to Figure 2 and assuming a train passing from intermediate circuit $B-C$ to intermediate circuit $D-E$. As the train enters track section D relay TD is deenergized closing its back contact 41 . Conductor L for intermediate circuit of section $B-C$ is now connected to conductor L for intermediate section DE via conductor 42 , back contact 41 closed and conductor 43 . By reason of back contact 41 being closed transformer TC is shunted from the circuit; but as front contact 44 opens, creating the enlarged intermediate circuit, the transformer TE is made available as a part of the enlarged intermediate circuit for communication between wayside and train. While the train is within this enlarged intermediate circuit, that is while any part of the train is within the track section D , communication carried on between the front and rear of the train, between the train and a wayside station, or between the train and a second train, should there be a second train in section $B-C$ or $D-E$, will be via the enlarged intermediate circuit which includes the track rails TR , the condensers AK , front contact 31 , conductor L , back contact 41 closed, conductor L , transformer TE , front contact 51 closed and condensers AE . Thus it is seen that the train is always in a communicating zone which is successively an intermediate circuit as for section $B-C$, an enlarged intermediate circuit as for sections $B-C$ plus $D-E$, the intermediate circuit for section $D-E$, etc., a travelling intermediate circuit or communicating zone being in reality created by this arrangement.

In Figure 5 a train in passing from one intermediate section, as B_1-C_1 , to another intermediate section, as D_1-E_1 , deenergizes the track circuit relay, as DT_1 , thus causing each of the two intermediate circuits, as for section B_1-C_1 (one including the track rail TR_1 and the other including the track rail TR_2) to be combined with the respective intermediate circuits of the adjacent section, as for section D_1-E_1 (one including the track rail TR_1 and the other including the track rail TR_2). When relay TD_1 is deenergized, back contact 185 is closed shunting transformer RC_1 and connecting conductor L_5 of section B_1-C_1 with conductor L_5 of section D_1-E_1 ; also back contact 185 is closed shunting transformer TC_1 and connecting conductor L_6 of section B_1-C_1 with conductor L_6 of section D_1-E_1 . Thus, for the period the train is in track circuit section D_1 , the intermediate circuits including the track rails TR_1 and TR_2 are enlarged covering both the sections B_1-C_1 and D_1-E_1 and including transformers RE_1 and TE_1 respectively. As the train travels over the railroad it creates for itself a prescribed communication zone travelling with the train which comprises the two intermediate circuits, one each for the track rails TR_1 and TR_2 .

In the two systems of communication herein described, as illustrated in Figures 1, 2 and 3 and 4 and 5, I have shown specifically how two sets of conversations, or communications, may be carried on at the same time. Should there be need for a third set of communications, or several additional sets of communications, to be carried on simultaneously with those described, it is obvious the same may be done by providing other, or several, radio frequency bands, each differing from the other and from those already used, as

the vehicle for transporting the additional sets of communications over the same circuit medium.

What I claim as new is:

5. 1. In a system adapted to simultaneously transmit a plurality of sets of communications between a railway train and the roadside, the combination comprising, transmitting and receiving devices on the train, transmitting and receiving devices on the roadside, said transmitting devices generating bands of electric current frequencies for conveying said sets of communications one band for each set, and circuit means including the track rails adapted to inductively connect said train carried transmitting devices with said roadside receiving devices and said roadside transmitting devices with said train-carried receiving devices, for transporting said electric current frequency bands.
10. 2. In a system adapted to simultaneously transmit two sets of communications between a railway train and the wayside, the combination comprising, audio frequency transmitting and receiving means on each said train and said wayside for transmitting and receiving one set of said communications, a radio frequency transmitting and receiving means on each said train and said wayside for transmitting and receiving the other set of said communications, and circuit means, including the track rails in multiple, electrically related to the train carried means and adapted to be connected to said transmitting and receiving means on the wayside for carrying said audio and radio current frequencies between said train and said wayside.
15. 3. In a system adapted to simultaneously transmit a plurality of sets of communications between a railway train and the wayside, the combination comprising, means on each said train and said wayside for transmitting and receiving a plurality of frequency bands, one band for each of said sets of communication, and circuit means in electrical relation with said train means adaptable to be selectively connected with said wayside transmitting and receiving means.
20. 4. In a system adapted to simultaneously transmit a plurality of sets of communications between two railway trains on the same track system, the combination comprising, means on each train for transmitting and receiving a plurality of frequency bands, each band carrying one of each sets of communications, and circuit means forming a communication zone travelling with the trains, electrically related to said train means, for connecting the transmitting and receiving means of one train with the transmitting and receiving means of the other train.
25. 5. In a system for carrying on two sets of communications between a railway train and a wayside station, a track system connecting communication devices on said train with communication devices on said wayside comprising, an intermediate circuit including one of the rails of the track, another intermediate circuit including the other rail of the track, both of said track rails being in inductive relation with the train devices, and means operated by the presence of the train on the track connecting one intermediate circuit with some of the wayside devices for transmitting to and receiving from the train one set of communications, and selective means for connecting the other intermediate circuit with other of the wayside devices for transmitting to and receiving from the train the other set of communications.
30. 6. In combination, a railway track formed in sections, a plurality of conductors parallel thereto, a radio frequency wayside station connected to a pair of said conductors, an audio frequency wayside station connected to another pair of said conductors, track relay controlled circuits for electrically connecting said radio frequency pair of conductors in operative relation with one rail of said track and means electrically connecting said audio frequency pair of conductors to the other rail of said track.
35. 7. In combination, a railway track, a plurality of pairs of conductors parallel thereto, a radio frequency wayside station connected to a pair of said conductors and an audio frequency wayside station connected to another pair of said conductors, a pair of transformers one having its secondary terminals connected to one of said rails and the other having its secondary terminals connected to the other of said rails, switches for connecting the primary of one of said transformers to one of said pairs of conductors and additional switches for connecting the primary of the other transformer to the other of said pair of conductors.
40. 8. In combination, a railway track, a plurality of pairs of conductors parallel thereto, a pair of transformers one having its secondary terminals connected to one of said rails and the other having its secondary terminals connected to the other of said rails, switches for connecting the primary of one of said transformers to one of said pairs of conductors, additional switches for connecting the primary of the other transformer to the other of said pair of conductors, an audio frequency wayside sending and receiving set connected to one of said pairs of conductors, a radio frequency wayside sending and receiving set connected to the other of said pairs of conductors, and a railway train on said track having an audio frequency receiving and sending set connected inductively to one rail of the track and a radio frequency receiving and sending set connected to the other rail of said track.
45. 9. In a train communicating system, the combination comprising, a first and a second communicating station for a train, a first and a second communicating station on the roadside, and means creating a transmission medium traveling with said train adapted to so connect together said stations that communication may be carried on between said first stations exclusively at the same time that communication is being carried on between said second stations exclusively.
50. 10. In a train communication system, the combination comprising, a first train station, a second train station, a first roadside station, a second roadside station, and means, controlled in part by the train and in part from a roadside station, adapted to continuously connect together said first stations and said second stations as the train travels over the railroad, so that uninterrupted communication between said first stations and uninterrupted communication between said second stations may be carried on simultaneously.
55. 11. In a train communication system, the combination comprising, a first train communicating station, a second train communicating station, a first roadside communicating station, a second roadside communicating station, wayside means, including a series of wayside circuits in communicative relation with said train stations, a wayside communication circuit connecting to each of said wayside stations, circuit controlling means

- associated with said series of circuits adapted to connect each of said series with said wayside communication circuit, and means associated with said communicating stations permitting exclusive communication between said first stations simultaneous with exclusive communication being carried on between said second stations.
12. In a train communicating system, the combination comprising, a first and a second communicating station on a train, a first and a second communicating station on the roadside, means traveling with the train adapted to connect together said stations, means in said stations for transmitting and receiving non-conflicting sets of communications simultaneously between said first stations and between said second stations, and means associated with said stations maintaining the distinct existence of each of the said sets of communication.
13. In a system for carrying on a set of communications between a car and the locomotive of a train and simultaneously a set of communications between said car and a wayside station, in combination, a plurality of communicating sets in the car, a communicating set in the locomotive harmonizing with one of the car sets, a communicating set in the wayside station harmonizing with another of said car sets, a circuit means on the wayside in normal inductive relationship with said car sets and the locomotive sets so that communication may be carried on thereover between the car and locomotive, means adapted to connect the wayside station set with said circuit means that communication may be carried on over said circuit means between the car and the wayside station at the same time that communication is under way between the car and the locomotive, and means associated with said car sets whereby the distinct characteristics of each set of communications is maintained.
14. In a system for simultaneously transmitting a plurality of sets of communications between a railway train and a wayside station, a stretch of track for the train, train carried means for simultaneously transmitting and receiving separate sets of communications, wayside station means for simultaneously transmitting and receiving said sets of communications, means electrically coupled with said train carried means and controlled by the presence of the train in said stretch forming a communication zone for said train to which the said sets of communications for and from said train are confined, and means operative from the wayside station for placing said wayside station in communicative relation with the means forming said zone.
15. In a system for simultaneous communication between the wayside and railway trains in a stretch of track, means on each train adapted to transmit communications to and receive communications from the wayside, means on the wayside adapted to simultaneously transmit and receive a plurality of communications, one for each train, and means associated with each train means and electrically controlled from said wayside for placing said wayside means in communicative relation with the said means on each of a plurality of said trains.
16. In a system for a plurality of communications simultaneously carried on between vehicles in a section of track, means on each vehicle adapted to simultaneously transmit and receive a plurality of communications, a communication zone for said vehicles within which communications between said vehicles are confined, and

means controlled by said trains for placing said vehicles in communicative relation with each other.

17. In a system for communication between two train stations and between one of said train stations and a wayside station, a channel for communications between said train stations, a different channel for communications between one of said train stations and the wayside station, and means associated with said channels maintaining the individuality of said communications in said stations.

18. The combination, in a railway communication system, comprising a stretch of track for a train, of a loop circuit including the running rails in said stretch, radio frequency current generating means located at separated points on a train and arranged for inductive co-operation with said loop circuit, and devices at each train point adapted to modulate and demodulate said radio frequency current whereby radio frequency signaling is effective between said train points through said loop circuit.

19. In a telephone system for inductively receiving on a train a plurality of carrier currents of different frequencies, a stretch of track including the two running rails for a train to run over, a conductive intermediate circuit, including electrical conductors, associated with the stretch of track and electrically closed with the stretch of track either occupied by a train or unoccupied, operative with a train running in either direction and adapted to change with a train moving over said running rails by additions to the circuit ahead of the train and subtractions from the circuit behind the train, said change being dependent upon the movement of the train, a winding located on said train in such manner that, with a train present on said running rails, the winding is disposed near to and separated by an air gap from one of said conductors of the intermediate circuit and, together with said conductor, constitutes an electrical transformer of which the winding serves as primary winding and the conductor as secondary, and receiver means carried on said train in circuit with said winding adapted to be responsive to a plurality of currents of different frequencies flowing in said intermediate circuit.

20. In combination, a railway train, rails in the track for said train to run on, means located at one point on the train for transmitting modulated carrier frequency current into a circuit which includes said running rails therein in multiple, and means located at a point remote from said train point and associated with said circuit responsive to said carrier frequency current flowing in said circuit due to said first mentioned means.

21. In a system of communication for railways, a transmitter at one station adapted to transmit electric current of carrier frequency modulated with electric current of other frequencies, a receiver in a station remote from said one station responsive to said carrier current and adapted to demodulate the same, and a circuit including the running rails of the railway track adapted to receive said carrier current from the transmitter at the one station and to transmit said carrier current to the receiver at said remote station, said carrier current flowing in the running rails in the same direction at any instant and returning to the point at which introduced into the rails through another path associated with said running rails.

22. In a train telephone system, a stretch of track for a train, a train on the track, a transmitting device comprising a carrier current generator and a modulator at one point on the train, a receiving device at another point on the train, and a circuit for conducting current from said transmitting device to said receiving device comprising the two track rails and a common return path so related to said rails that current flows through the rails in multiple to points substantially ahead of and in rear of the train.
23. In a train telephone system, a stretch of track for a train, a train on the track, a transmitting device comprising a carrier current generator and a modulator on the train, a receiving device on the train, a wayside station, a transmitting device comprising a carrier current generator and a modulator at said station, a receiving device at said station, a circuit associated with said train carried devices comprising the two track rails and a common return path so related to the rails that current flows through the rails in multiple to points substantially ahead of and in the rear of the train, and a second circuit connecting said first circuit to said wayside station devices.
24. In a system for transmitting one set of signals between two vehicles of a railway train and another set of signals between one of said vehicles and a wayside station, in combination, a circuit carried on one of said vehicles for transmitting and receiving two sets of signals, each of a different current frequency, a circuit carried on the other of said vehicles for transmitting and receiving a set of signals of current of one of said frequencies, a circuit at a wayside station for transmitting and receiving a set of signals of the other of said frequencies, and an intermediate circuit including the track rails in multiple electrically connecting the transmitting and receiving circuits of said vehicles and said wayside station for conducting the signal currents therebetween.
25. In an electric transmission system for railways, in combination, a stretch of railway track, a first station and a second station each associated with said stretch of track at points remote from each other, a transmitter at said first station adapted to transmit electric current of carrier frequency modulated with current of a different frequency, receiving apparatus at said second station responsive to said carrier current and arranged to demodulate said current, and a circuit for conducting the current from said transmitter to said receiving apparatus comprising the two track rails and a common return path so related to the rails that the current from the transmitter flows to the receiving apparatus through the track rails in multiple.
26. In a train operating system, in combination, a railway line, a plurality of vehicles on said line, a wayside station, apparatus at said station for transmitting to each vehicle electric current of distinctive character, said current being different for each vehicle, a receiver on each vehicle responsive only to current intended for that vehicle, and a circuit in electrical relation with the apparatus at said station and the receiver on each vehicle for conveying said currents from the station to the respective vehicles.
27. In a system for simultaneous transmission to a railway train of an electric current of audio frequency and an electric current of radio frequency from different wayside stations, in combination, a stretch of track for the train, receiving apparatus on the train selectively responsive to each of said currents, a plurality of wayside stations, apparatus at one of said stations for transmitting electric current of radio frequency, apparatus at another station for transmitting electric current of audio frequency, and an intermediate circuit in electrical relation with said receiving apparatus on said train and adapted to be connected to the transmitting apparatus at said wayside stations for carrying the electric signal currents between said stations and said train.
28. The combination with a stretch of track and a train operating thereon, of two locations spaced apart on the train, a transmitting circuit including a generator of current of a predetermined frequency at each location, a receiving circuit at each location including a filter tuned to pass only current of the frequency of the generator at the opposite station, and a transmission circuit continuously connecting said transmitting and receiving circuits as the train moves along said track, said transmission circuit comprising the two track rails in multiple and a common return path.
29. In a system for simultaneously transmitting a plurality of non-conflicting sets of communications between a railway train and the wayside in which a separate frequency band of electric current is employed for transporting each set of said communications, means carried on said train and means located on the wayside for supplying, transmitting and receiving said bands of current frequencies on the train and on the wayside, respectively, circuit means on the wayside for receiving the transmitted current from either said train or said wayside, and means operable to place said train means in electric relation with said wayside means via said circuit means for the transference between said train and said wayside of one or more than one of said frequency bands.

ARCHIBALD G. SHAVER.
